ACCOUNTING MACHINE

Walter Scheerer and Kurt Locklair, Berlin-Lichterfelde, Germany, assignors to International Business Machines Corp., New York, N. Y., a corporation of New York

Application December 15, 1939, Serial No. 309,407
In Germany January 10, 1939

12 Claims. (Cl. 235—61.6)

This invention relates to improvements in accounting machines which are equipped with electric calculating mechanisms for the performance of calculating operations.

One of the objects of the invention is the application of electromagnetic relays to establish contact combinations, one relay being provided for each denominational position and having several double wound magnets and related contacts for effecting the contact combinations necessary for the representation of the values 0-9. The number of double wound magnets per relay is limited to four at the utmost for the values 0-9, whereby the principal success of the inventive idea is secured.

It is proposed to bring the several double wound magnets under the effect of current impulse emitters, so as to be energized upon the entry of digit values into the machine by means of keys or under the control of record cards, whereby they control, upon the energization of the magnet windings the contacts associated with them.

It is evident that the calculating relays may be used for the purpose of addition as well as for subtraction as will become apparent in the description of the embodiment of the invention shown in the drawings, given hereafter.

In a preferred embodiment of the invention as shown in the drawings, tens carry operations are effected at the close of the value entry portion of each cycle, and in a modified form, the tens carry operations are effected at once as they present themselves during the entry of the value.

Other objects of the invention will be pointed out in the following description and claims and illustrated in the accompanying drawings, which disclose, by way of example, the principle of the invention and the best mode, which has been contemplated, of applying that principle.

In the drawings:

Figs. 1a to d show a relay of one calculating position, Fig. 1a being a section according to the line a—a of Fig. 1b, Fig. 1b a profile view, Fig. 1c a top view, and Fig. 1d a section according to the line d—d of Fig. 1a.

Fig. 2 shows a group of individual contacts of the contact system by indicating schematically their tie-up with the magnet systems.

Fig. 3 shows in the same manner another group of individual contacts of the contact system.

Figs. 4 and 4a show a wiring diagram of the first embodiment of the calculating mechanism, Fig. 4a being a continuation of Fig. 4.

Fig. 5 is a timing chart of the cam contacts shown on Figs. 4 and 4a.

Fig. 6 is a timing chart for a selected calculating example whereby the diagonal crosshatching represents the closing times of contacts and the longitudinal crosshatching represents circuit times for the exciting windings.

Fig. 7 shows at which point of time, with the second embodiment, tens carry operations are effected.

Fig. 8 is a modification of the wiring diagram shown in Figs. 4 and 4a.

Fig. 9 is a timing chart indicating the closing times of the cam contacts shown in Fig. 8.

Referring now to the drawings, and particularly to Figs. 1a and 1b, a relay provided for each calculating position consists of four magnet systems

generally designated M0, M1, M2, and M3. These individual magnets are fastened to a support 10, carrying also a group of contacts associated with the magnets. The group of contacts consists of the individual contacts 0a, 0b, 0c, 1a, 1b, 1c, 2a, 2b, 2c, 3a, and 3c which are identified later in the adding operations and of the individual contacts 1, 2, 3, 4, 5, 6, 7, 8, 9, 0, z which are employed in total taking as will be described hereinafter. The arrangement of the contacts with respect to each other is designated by the record of their reference characters at the left of Fig. 1b. Each of the magnet systems M0 to M3 consists of a core 11 and yoke 13 fastened thereto by means of a screw 12. The core 11 is surrounded by a coil 14, on which are two windings, i. e., for the magnet M0 windings 0I and 0II, for the magnet M1 windings 1I and 1II, for the magnet M2 windings 2I and 2II, for the magnet M3 the windings 3I and 3II. To the yoke 13 by means of plate springs 15 and 16 respectively, one light and one relatively heavy armature are fastened. These armatures are A0I and A0II, A1I and A1II, etc., the suffix "I" being indicative of the light armature, and "II" indicating the heavier armature.

As will be described below, the windings of each magnet are energized in a differential manner at a predetermined voltage during the operation of the calculating device. The attraction of the lighter or of the heavier armature of a magnet depends on which winding of that magnet is energized.

Upon the flow of current through the winding 0I of the magnet M0, for example, the lighter armature A0I is attracted, while the heavier armature A0II remains in its home position due to the fact that the number of ampere turns of the winding 0I does not produce a sufficient magnetization of the magnet core.

The winding 0II has a higher number of ampere turns than the winding 0I, so that only

upon the flow of current through the winding 0II is the heavier armature A0II attracted. A current flow through the winding 0II would, obviously, cause the attraction of the armature A0I as well.

When both armatures A0I and A0II are attracted a current flow through one of the two windings 0I and 0II will be sufficient to keep the armatures in attracted condition. Upon the de-energization of the windings the armature 0I falls away more quickly than the armature 0II. The conditions just explained for the movements of the armature of the magnet M0 apply also to the movements of the armatures of the magnets M1, M2 and M3.

The adding and total contacts are arranged between the magnets M0 and M2 and the magnets M1 and M3. The individual contacts consist of two contact springs each, being kept at a distance from one another and from the contact springs of the adjacent contacts by insulating pieces 17. The contact block formed thereby is surrounded by a frame 18, which is fastened to the support 10. On the frame 18 at 19 several bails are mounted, bearing the reference characters B0I, B0II, B1I, B1II, B2I, B2II, B3I, B3II. Each armature of the magnets is connected with one of these bails by means of bars 20 and 21, for example, the armature A0I with the bail B0I and the armature A0II with the bail B0II. Each armature is kept in its home position by the bias of the plate springs 15 and 16, respectively, whereby the bail connected with it is caused to rest against stops 22 of the frame 18. If by the energization of one of the magnets the attraction of its armature towards the part of the core 11 which is bent at its upper end takes place, the bail which is connected to the armature by bar 20 or 21 and is moved from its home position in which, as is shown in Fig. 1a is in a downward direction. Supports 23 and hooks 24 mounted at the contact springs transmit the movement of the bail to individual contact springs. The manner in which this is done is shown in Figs. 2 and 3 in which the supports 23 and hooks 24 for the contact springs of the individual contacts are indicated symbolically.

From Fig. 2 it may be seen that the special contact springs (see contacts 1b and 2b) have special spring plates 25 coordinated with them, and are likewise equipped with supports 23 and hooks 24. Thereby upon the closing and the opening of the contacts 1b and 2b by the bails, special conditions are created.

The adding contacts are connected in a pre-determined manner with the windings of the magnets M0, M1, M2, and M3 in series. The bails B0I, B0II, etc., influencing the contact springs determine by their position in connection with the switching elements specified below the current supply to the windings of the magnet systems M0, M1, M2, and M3.

Hereafter the connection of the windings with the adding contacts of the magnets and the control of the adding contacts by the bails is described with reference to Fig. 2 and the circuits are illustrated in Fig. 4.

Contacts 0a and 0b are connected in series with windings 0I. Contacts 0a are closed in the event that the bail B0I is out of home position and at least one of the bails B0II and B3II is in home position, or if the bail B3II is out of home position and the bail B0II in home position, in the latter case the position of the bail B0I

being immaterial. Contacts 0b are opened, if at least one of the bails B1II and B2II is moved out of home position and the bail B0II is in home position.

5 Contacts 0c are connected in series with the winding 0II, and are closed if the bail B0I is moved out of home position. Contacts 1a and 1b are connected in series with winding 1I. Contacts 1a are closed, if at least one, of the bails B0II and B1I is out of home position and if at least one of the bails B1II and B3II is in home position. Contacts 1b are opened, if the bails B0II and B2I are out of home position. In the latter case the bails B0I and B3I retain the position occupied by them following the energizations of their magnets due to the curvature of the spring plate 25. That is, for example, if the bails B0II and B2I are out of home position and if one of the bails B0I and B3I is still in home position, the lower contact spring is only bent at its extreme end for the purpose of opening the contact 1b. Thus it will be appreciated that bails B0II and B2I are the primary controlling factors and bails B0I and B3I are the secondary controlling factors in the operation of contacts 1b, the latter bails being effective for independent control of the contacts only when the former bails remain in home position. The same principle of operation is provided for special contacts 2b which are operated by bails 0I, 3I and 1I.

Contacts 1c are connected in series with the winding 1II and are closed if the bail B1I is out of home position.

35 Contacts 2a and 2b are connected in series with the winding 2I.

Contacts 2a are closed, if at least one of the bails B1II and B2I is out of home position and at least one of the bails B2II and B3II is in home position, whereas contacts 2b are opened, if the bails B0I and B3I are out of home position.

40 Contacts 2c are connected in series with the winding 2II, and these contacts are closed whenever bail B2I is out of home position.

45 In a corresponding manner, winding 3I and contacts 3a are connected in series as are winding 3II and the parallelly connected contacts 3c and N. Contacts 3a are closed if at least one of the bails B2II and B3I is out of home position and the bail B3II is in its home position.

50 Contacts 3c and N, which are in parallel with each other and in series with winding 3II, are operated if any one of the bails associated therewith is out of the home position.

55 Fig. 3 shows the control of the total contacts by the various bails. Contacts 1 are closed if the bails B1II, B2I and B3II are altogether in their home position. Total contacts 2 are closed if the bails B0II and B1II are out of their home position, contacts 3 are closed if the bails B0II and B2II are out of their home position, and contacts 4 are closed if the bails B0II and B3II are out of their home position. Total contacts 5 are closed as long as bails B0II, B2II and B3I all remain in their home position. Contacts 6 are closed upon movement of the bails B1II and B2II out of their home position, as are contacts 7 upon movement of bails B1II and B3II out of the home position. If the bails B0II, B1II, and B3II are altogether in home position, contacts 8 remain closed.

60 Total contacts 9 are closed if the bails B2II and B3I are out of their home position.

65 The closed condition of contacts 0 depends upon the bails B0II, B1II and B2II all remain-

ing in home position. Lastly, total contacts z are closed if the bails $B2II$ and $B3II$ are out of their home position.

From the above record it appears that the position of the bails with respect to the position of the armature coordinated with the bails determines the condition of the adding and total contacts. The condition of the adding contacts determines according to its connection in series with exciting windings of the magnets, which of these windings may eventually receive a current supply. If by further wiring measures the conditions for a current supply to these windings are existing, a current flow influences in the already described manner the armatures of the corresponding magnets so that other predetermined armature positions are initiated. The bails connected with the armatures cause a new contact combination as described hereinbefore. The conditions for a current supply to the windings of the magnets which are connected in series with closed contacts of the contact system appear from the description of the wiring diagram (Figs. 4 and 4a) following below.

Two devices are indicated, which may be used for the entry of digit values into the calculating mechanism, i. e., first a value entry device, analyzing in a known manner record cards while in motion for the purpose of identifying the value holes punched into the record cards and secondly a key controlled value entry device with which each digit value is entered by the operation of several keys. By means of plug connections each of these value entry devices may be connected with the calculating mechanism, so that this one may be controlled selectively by record cards or manually. Further, means are provided to enter each predetermined digit value additively or subtractively into the calculating mechanism. The latter is done by entering the complementary value. Means are also provided to read out a product calculated in the calculating mechanism to a printing bank or the like. Of the calculating mechanism only the three lowest calculating positions are shown, but from Figs. 4 and 4a it may readily be recognized how further positions are to receive entries.

For effecting current impulses upon the magnets of all calculating positions, two impulse emitters $J1$ and JII are provided. These effect the transmission of current impulses to the magnets, as is indicated in Fig. 5 by the cross-hatched portions in columns $J1$ and JII . The current supply to the magnets is, however, still dependent on contacts of relays, being called hereafter brush relays, because with the entry of values by means of record cards these relays are controlled by circuits flowing from the analyzing brushes. The energization of a brush relay, one of which is provided for each position, is dependent upon the position of a value hole in a column of a record card or upon the actuation of one of the keys where the entry of the values is key controlled.

The resetting to zero of the calculating mechanism is effected in a simple manner by rendering all magnets currentless by means of a resetting contact LK , whereby all bails $B1I$, $B1II$, $B2I$, $B2II$, $B3I$, $B3II$ are returned to their home position and therewith impart to the contacts of the contact system a position corresponding to "0."

The analysis of holes in record cards is effected in a well known manner wherein the record card is moved along between a contact

roll 30 and a series of analyzing brushes 31 . For each card column one brush 31 is provided. The contact roll 30 is connected through a card contact KK to the negative line 32 of a power source.

5 The card contact is in a known manner controlled by the cards and is only closed, if a card is between the contact roll 30 and the brushes 31 . Each brush 31 is connected conductively with plug socket 33 to permit each position of the analyzing mechanism to be connected by means of a flexible plug wire selectively with any position of the calculating mechanism.

For the entry of the value by keys for each calculating position, nine keys with key contacts 34 are provided, whereby the key contacts related to a calculating position are connected jointly with a plug socket 35 for the selective connection with any position of the calculating mechanism. A commutator 36 (Fig. 4a) is pro-

20 vided for all positions in common and consists of a revolving pair of brushes 37 , wiping over a semi-circular common strip 38 and individual segments 39 . Each segment 39 is designated with one of the digits 0-9 and accordingly connected by the lines 40 with the related key contacts 34 . The common strip 38 is connected via the line 41 with the negative line 32 .

During the revolution of the pair of brushes 37 when using key controlled entry of the values and also upon movement of the record cards under the analyzing brushes when using record card controlled entry of the values, the plug sockets 35 and 33 are connected at predetermined points of time according to the digit value to be entered with the negative line 32 of the power source. The points of time which are coordinated with the different numeral values are occurring with each value entry cycle in a sequence such as is indicated in Fig. 5 column 40 entitled "Hole," so that it is started with the digit index point "9." If plug connections are made from the sockets 33 or 35 to the plug sockets 42 of the calculating mechanism, then the sockets 42 are capable of being connected 45 with the negative line 32 at each digit point of time to effect entry of a predetermined value in the calculating mechanism.

This connection of the socket 42 with the negative line at fixed points of time effects the 50 connection with further switching elements due to the operativeness of the brush relay, the windings of which are indicated for the first calculating position as $BR1S$, $BR1H$. The windings of the brush relays $BR1$, $BR2$, $BR3$, etc., of all positions are connected by means of a common bar 43 via conductor 44 to positive line 45 .

If one of the sockets 42 , for example, the one for the lowest calculating position, is connected by one of the value entry devices at a predetermined point of time in accordance with the digit value with the negative line 32 a circuit is completed from the conductor 45 through the conductor 44 , the bar 43 , the brush relay winding $BR1A$, contacts $VRS1$ to the plug socket 42 .

60 Therewith an energization of the brush relay $BR1$ by its winding $BR1A$ is effected whereby the brush relay closes contacts $BR1a$ which are connected in series with the winding $BR1H$. Winding $BR1H$ receives therewith current as long as a cam contact $N1$ is closed (see Fig. 5) whereby the brush relay is kept in energized condition. From Fig. 5 it appears that the holding circuit for the brush relay remains closed up to the close of the value entry cycle. It is obvious, however, that the brush relay remains energized following the en-

try of a value during a period corresponding to the magnitude of the value to be entered. The brush relay effects, during this time, by the operation of its contacts in a manner to be described later on, the passage of current from the impulse emitters to the magnets of the relay of the corresponding calculating position.

The energization of the brush relay at the time of the entry signifies an additive entry of a digit value. If a subtractive entry of a value has to be effected into the calculating mechanism, contacts SK are closed. Therewith the following circuit is closed: From the positive line 45 through the conductor 46, relay coil VRS, relay coil VRS', contacts SK, now closed, conductors 47 and 48 to negative line 32. The subtraction relay VRS transfers its contacts VRS'! from the position shown, and the subtraction relays VRS' likewise closes a contact VRS'!. Thereby at the start of each value entry cycle the following circuit is closed: Positive line 45, conductor 44, bar 43, winding BR1A of the brush relay, contact VRS'!, cam contacts N4, conductor 48, negative line 32. As may be seen from Fig. 5, the cam contact N4 is closed at a point of time, corresponding to the digit value 9. The short energization of the brush relay caused thereby through the winding BR1A initiates again a holding circuit for the winding BR1H through the cam contact N1, being maintained up to the close of the value entry cycle. If, at a predetermined point of time in the entry cycle, the plug socket 42 is connected with the negative line, a circuit flows from the conductor 45 through conductor 44, winding BR1S, contacts VRS'! to the socket 42. The winding BR1S is wound oppositely to the winding BR1H on the brush relay. The current flow through the winding BR1S annuls therewith the effect of the holding circuit through the winding BR1H, so that the brush relay remains deenergized and following the breaking of its holding circuit remains also deenergized even though current flows through the winding BR1S.

If therefore the contacts SK are closed, i. e., if the values are to be entered subtractively into the calculating mechanism, each brush relay is kept energized from the start of the value entry cycle, i. e., from the digit point of time "9" up to the point of time of the entry of a digit value. This causes current to be supplied to the individual magnets of the calculating mechanism under the control of the brush relay to effect an entry of arithmetical values into the magnets which are "9" complements. With this complementary entry of arithmetical values, provision must be made so that with each value entry in the position of the lowest order a "1" is entered additively in a manner well known in the art.

The switching devices dealt with in the foregoing for the position of the lowest order BR1S, BR1A and BR1H of the brush relay are also provided for each further position. The windings of the brush relays of these positions are indicated accordingly BR2S, BR2A, BR2H, and BR3S, etc. Besides the contacts described for the first position for each of the following positions there are still provided carry contacts UR1b (for the second position) UR2b (for the third position) etc., serving for the tens carry operation. If these carry contacts are in position of rest, as shown in Figs. 4 and 4a, there is no change in the line connections from that described for the first position. If, however, for example the second calculating position, the switch contact UR1b is reversed, the winding BR2A of the brush relay of

the second position is connected in series with cam contacts N2 which, according to Fig. 5 are closed for a short time after the completion of a value entry cycle. At that time the following circuit is closed: Positive line 45, conductor 44, bar 43, BR2A, UR1b, now transferred, contacts N2, conductor 48, to negative line 32. For each of the contacts UR1b, UR2b, etc., there is a separate pair of contacts N2 to obviate the possibility of back circuits. Immediately after the value entry portion of the cycle the brush relay is energized by the winding BR2A for a short time, whereby the brush relay permits an impulse transmission to the magnets for this period of time. The time is sufficient to effect the entry of a "1" into the magnets. Presently the manner in which the magnets of the individual positions are connected with the impulse transmitters and with the brush relay contacts will be described.

The free ends of the windings 0I up to 3II shown in Fig. 2 of the magnets M0 up to M3 are connected by a conductive bar 49 with one another. From this bar a current path flows over the resetting contact LK, a conductor 50 to negative line 32, so that during the operation of the calculating mechanism the bar 49 is connected with the minus potential. The ends of the contacts 0b, 1b, 2b, and 3a in each calculating position are connected by a common bar, designated 51, which in the first calculating position may be brought into conductive connection with the positive line 45, through a brush relay contact BR1c, in the second position through a brush relay contact BR2c, etc., by means of an impulse emitter JI which is common to all positions. Lines 53 are provided for the connection of the contacts BR1c, BR2c, etc., with the impulse emitter JI. The free ends of the contacts 0c, 1c, 2c, 3c, and N (Fig. 2) in each calculating position are connected with one another by a common bar 52. The bar 52 of the first calculating position is connected with a middle contact spring 54 of contacts BR1d of the brush relay. By means of these contacts, the bar 52 may be connected either through the contact spring 55 and the conductor 57 directly, or through the contact spring 56 and impulse emitter JII, to positive line 45. Correspondingly the second calculating position is provided with contacts BR2d, the third calculating position with contacts BR3d, etc. All springs 55 of these contacts are connected by conductor 57 and all springs 55 by conductor 58.

As for the total contacts (Fig. 3) the contacts 0-9 for each calculating position are connected with one another by a common bar 60 which is also connected to a plug socket 61. The similarly numbered contacts 0-9 of all calculating positions are connected jointly by conductors 62 and 40 with the corresponding individual contacts 39 of the commutator 36. The plug sockets 61 are provided for the reading out of values computed in the calculating mechanism in conjunction with the total contacts.

The read out of a value represented by closed total contacts in the calculating mechanism is effected by means of plug connections from the plug sockets 61 to say the plug sockets 63 of a printing bank, each printing bank position being supplied with such a plug socket 63. In Fig. 4a, at the bottom, a printing bank of the well known type is indicated, on which type bars are arrested while in motion at predetermined points of time by magnets SM1, SM2, SM3, etc., whereby the type bars are positioned in accordance with the digit values for the purpose of printing

these values on a record sheet. The type bars are moved synchronously with the brushes 31 of the commutator 36 up to their stoppage. All print magnets SM1, etc., are connected through contacts SWK to positive line 45. If the contacts SWK are closed under machine control or manually, what occurs, if a value entered into the calculating mechanism is to be identified by print, is that magnets SM1, etc., are energized at predetermined points of time in accordance with closed total contacts. For the magnet SM1, this is done in the following way: Positive line 45, printing bank contacts SWK, now closed, magnet SM1, plug socket 63 of the position of the lowest order, plug connection from 63 to 61, plug socket 61, bar 60, total contacts 5, for example, conductors 62 and 40, commutator contacts 39 (segment 5) brushes 31, common strip 38, conductor 41, to negative line 32.

The total contacts z (Figs. 3, 4, and 4a) serve for the tens carry and are always closed after the total contacts 9 have been closed during a calculating cycle and remain closed up to the opening of contacts 9 by operations of the calculating mechanism which will be described below. With the common current bar 49 of the magnet windings of the magnet system in each calculating position there is also connected a tens carry relay, i. e., UR1 for the position of the lowest order, UR2 for the position of the next higher order, etc. In the position of the lowest order the tens carry relay UR1 is connected with contacts z of this position and also with a contact BR1b of the brush relay in this position and with the impulse emitter JI in series.

If the total contacts z of the position of the lowest order are closed and furthermore the brush relay of the lowest position is energized, which according to the description given below is the case with the change of the contact positions from a combination corresponding to the digit "9" to a combination corresponding to the digit "0," the following circuit is closed through emitter JI: Positive line 45, impulse emitter JI, brush relay contacts BR1b, tens carry contacts z , tens carry relay UR1, resetting contacts LK, conductor 50, to negative line 32. The energization of the tens carry relay UR1 thereby initiates the closing of its holding contact UR1a.

In the following calculating positions the relay UR2 is similarly connected in series with contacts UR2a, the relay UR3 with the contact UR3a, etc. The contacts UR1a, etc., are connected by a conductor 10 with each other and with cam contacts N3. If during a calculating cycle a tens carry relay has been energized, cam contacts N3 maintain a holding circuit, flowing, e. g., for UR1 from positive line 45, through contacts N3, UR1a, UR1, LK, wire 50 to negative line 32. The closing time of the cam contacts N3, as may be seen from Fig. 5, begins with each calculating cycle and ends after the opening of cam contacts N2, which, as already mentioned control, in the second calculating position in conjunction with closed contacts UR1b after a calculating cycle, the transfer of the "1" to this position of the calculating mechanism. The contacts UR1b closed with the energization of the tens carry relay UR1. Therefore it may be said that the energization of UR1 of a calculating operation causes the transfer of a "1" to the second calculating position.

If in the second calculating position at the close of a calculating cycle there is a contact combination corresponding to the digit value "9,"

i. e., if also in this position the contact z is closed this causes simultaneously with the tens transfer to the second position a tens carry to the third position. For this purpose instead of the brush relay contacts BR1b provided for the lowest position there is provided brush relay contacts BR2b, BR3b, etc., for each of the other calculating positions. The middle contact spring 11 of each set of commutator contacts is connected with the contact z of the same position, the lower contact spring 12 is connected by the conductor 53 with the impulse emitter JI, and the upper contact spring 13 is connected over a conductor 74 with the tens carry relay of the position of the next lower order, e. g., UR1.

If in the lowest calculating position during the calculating cycle the tens carry relay UR1 has been energized and if at the end of this working cycle there is a contact combination in the next higher calculating position, corresponding to the digit value "9," so that in this position contacts z are closed, then the holding circuit for the tens carry relay UR1 of the lowest position causes also an energization of the tens carry relay UR2 of the second position. The relay UR2 is then within the following circuit: Positive line 45, cam contacts N3, conductor 70, contacts UR1a, conductor 74, brush relay contacts BR2b (Fig. 4a) contacts z of the second position, tens carry relay UR2, bar 49, contacts LK, conductor 50, to negative line 32. Therewith the tens carry relays of the first and of the second calculating positions are connected in parallel. Both relays cause a change in their contacts UR1b (for the brush relay of the second position) and UR2b (for the brush relay of the third position), so that the brush relays of the second and the third positions control a carry of "1" after the value entry cycle during the closing time of the cam contacts N2.

As the relay provided for each position, consisting of the magnets and their contacts and the switching means coating with it have already been described, it now is advisable to set forth predetermined arithmetic problem to illustrate the operation of the calculating mechanism particularly with regard to the energization of the windings of the magnets and the closing of the contacts of the system.

Let it be assumed first of all, that during the time from A—B in Fig. 6 the calculating relays are currentless, which condition is present upon switching off of the power source or upon the opening of the resetting contacts LK. Between points of time B and C the calculating relays are supplied with current and then from the point of time C the digit value "9" is introduced in a position of the calculating mechanism, the value entry portion of the cycle lasting up to the point of time D. From D the relays remain energized up to E when the digit value "2" is entered into the same position into which the digit value "9" has already been entered. The entry of the digit value "2" lasts up to the point of time F. From the point of time F up to the point of time G it may be assumed that a tens carry from the next lower position is effected, so that to the sum of "9" and "2" a "1" is added in the position to be handled. During the time G—H the relay structure remains energized.

Fig. 6 shows the relationships on the basis of the assumed arithmetic problems, the intervals AB, BC, DE, and GH may be longer than indicated in Fig. 6, whereas the value entry time CD for the digit value "9," EF for the digit value

"2" and FG for the digit value "1" (tens carry) are determined by the size of the digit values. The time being required for the entry of the digit values "1"- "9" are to be seen from Fig. 5, where the same scale is applied as in Fig. 6 for the time of the entry of the values "9," "2" and "1." With record card control, the times shown in Fig. 5 are repeated with each record card feed so that there is always a possible value entry from "9" up to "0" and a possible tens carry operation between "0" and "11." Accordingly, the times CD, EF and FG of Fig. 6 correspond with the digit times shown in Fig. 5 as follows: CD from "9" to "0," EF from "2" to "0" and FG from "0" up to "11."

If the device is currentless (time AB, Fig. 6) the contacts 0b, 1b, 2b, N, 0, 1, 5, and 8 are closed, as no armatures of the relays are attracted and all bails B0I-B2II are in home position. This contact combination is without any importance.

If the current is switched on, the condition of each calculating relay is at once changed, as the windings 3II are energized in the following manner: Positive line 45, wire 57, contact springs 55 and 54, bar 52, contacts N, winding 3II, bar 49, contacts LK, wire 50, to negative line 32. The current flow through each winding 3II causes the attraction of all armatures A3I and A3II, whereby the bails B3I and B3II are moved out of their home position. Thus contacts N, 1, 5, and 8 are opened and the contacts 6a and 3c are closed. Of the total contacts only the contacts 0 remain closed. That means that the relay of each calculating position has obtained a combination of closed contacts representing the digit value 0. In each relay this contact combination is maintained until a value entry is effected. If the contacts SWK, were closed the printing blank would print a zero in each position.

If shortly before the point of time C (Fig. 6) the entry of the digit "9" into a calculating position is started, e. g., into the second position, the entry causes energization of the brush relay of this position as already described from "9" up to "0." The entry also causes for this time a closing of the contacts BR2b, BR2c, BR2d and therewith an alternating control of the calculating relay by the impulse emitters JI and JII. With the transfer of contacts BR2d at the point of time of the entry, the contacts of the impulse emitter JII are closed, so that the transfer does not change the condition of the relay, even though the current path 57, 55, 54, 52, etc., is broken, since JII, 56, 54, 52, etc., forms a parallel path to maintain the relay.

In connection with the digit point of time "9," i. e., at the point of time C, the impulse emitter JI effects the current supply to the calculating relay and the contacts of emitter JII open. Thus, the winding 3II becomes currentless at this time so that the armatures A3I and A3II fall off, i. e., A3I more quickly than A3II. The falling off of the armature A3I causes opening of contacts 3c, the falling off of the armature A3II an opening of the contact 0a and a closing of the contact 1. On account of the slow falling off of the armature A3II the opening of the contact 0a is delayed so long by the bail B3II, that the current impulse of the impulse emitter JI may still reach the coil 0I through the contacts 0b and 0a. The resulting energization of the magnet M0 causes an attraction of the armature A0I, whereby its bail B0I closes the contacts 0c and 0a. Thereupon the current supply to the

calculating relay is effected by the impulse emitter JII. This causes a current flow through the coil 0II through the contact 0c, before the armature A0I can fall off due to the deenergization of the coil controlled by the impulse emitter JI. The current flow through the coil 0II energizes the magnet system M0 in such a way that both armatures A0I and A0II are attracted. The armature A0II causes through the bail B0II connected with it a closing of the contact 1a and an opening of the contact 0. Of the total contacts there remains, after the influence of the impulse emitters JI and JII between the digit points of time "9" and "8," only contacts 1 closed, i. e., the relay of this calculating position has been brought to the digit value "1." After the digit point of time "8" (Fig. 6) there is again effected a current supply to the relay by the impulse emitter JI. The winding 0II becomes currentless as the contacts of JII are opened. In its place the winding 0I is energized through the current impulse emitted JI and the contacts 0a, 0b, so that the armature A0I and A0II remain attracted. Simultaneously the winding 1I is energized over the contacts 1a and 1b. Owing to the current flow through the winding 1I the armature A1I is attracted and, by means of the bail B1I, the contact 1c is closed. The contact 1a is kept closed besides by the bail B0II, in the same manner as by the bail B1I.

The current supply coming thereafter by way of impulse emitter JII causes a current flow through contacts 1c and winding 1II. The winding 1I does no longer receive current for the energization of the magnet M1, so that magnet M1 is now only energized by the winding 1II. Thus the armature A1II is attracted, while the armature A1I remains attracted. The same refers to the magnet M2, the winding 0I of which is now currentless and the winding 0II of which is receiving current over the contact 0c, so that the armatures A0I and A0II remain attracted. As the bail B0II of the armature A0II is already out of home position, the contact 0b remains closed despite the movement of the bail B1II with the attraction of the armature A1II. The bail B1II closes the contacts 2a and 2, whereas it opens contacts 1, so that of the total contacts, contacts 2 only are closed at this time.

After the digit point of time "7," the winding 2I is energized by the impulse emitter JI over the contacts 2a and 2b. The current flow through the winding 2I causes armature A2I to be attracted and therewith the bail B2I leaves its home position, whereby contacts 2c are closed. Although the winding 0II becomes currentless, the winding 0I, in receiving current through the contacts 0a and 0b, takes care of the energization of the magnet M0, so that the armature A0I and A0II remain attracted. The bails B0II and B2I cause contacts 1b to open by virtue of their action on spring plate 25. The winding 1II of the magnet M1 cannot receive current from the impulse emitter JI and the winding 1I cannot receive current on account of the opened contacts 1b, so that the energization of the magnet M1 ceases. Therewith the armatures A1I and A1II fall off, whereby the bail B1I opens contacts 1c and the bail B1II opens contacts 2. The current supply is now again controlled by the impulse emitter JII, whereby through the contacts 2c the winding 2II is energized and therewith effects the energization of the magnet M2 despite the deenergization of the winding 2I, so that the armature A2I is kept attracted and the armature A2II is attracted. Therewith the bail B2II closes

the contacts 3a. The energization of the magnet M0 is maintained despite of the deenergization of the winding 0I, as the winding 0II is again energized through contacts 0c, so that the armatures A0I and A0II remain attracted. As now the bails B0II and B2II are both out of home position, total contacts 3 are closed.

After the digit point of time "6" the emitter JI completes a circuit through contacts 3a to energize winding 3I and through the contacts 0a and 0b to energize the winding 0I instead of the winding 0II. Thereby the armature A3I is attracted while the armatures A0I and A0II remain attracted. The bail B3I is moved out of home position, closes the contacts 3c and separates in common with the bail B0I, being already moved out of home position, the contacts 2b, so that the winding 2I cannot receive current. As the winding 2II is currentless due to the change of the impulse emitters, the energization of the magnet M2 ceases, so that the armatures A2I and A2II fall off. Upon the bail B2II returning to home position, the bail B3I keeps the contacts 3a closed. The bail B2II opens the contacts 3. When the bail B2II returns to home position, the contacts 2a and 2c are opened. The following current supply through the impulse emitter JII flows by way of the contacts 0c to the winding 0II and over the contacts 3c to the winding 3II. This causes, in spite of the deenergization of the windings 0I and 3I, both armatures A0I and A0II of the magnet M0 to remain attracted. Magnet windings 3I and 3II become energized to attract their armatures A3I and A3II. The bail B3II leaves its home position and opens the contacts 0a, as the bails B0I and B0II are also out of home position. The bail B3II also opens the contacts 3a and closes the total contact 4.

After the digit point of time "5," the current supply is again effected through the impulse emitter JI, whereby the windings 0II and 3II become currentless. The winding 0I cannot receive current due to the opened contact 0a nor the winding 3I due to the opened contacts 3a, so the magnets M0 and M3 are deenergized. Thereby the armatures A0I, A0II, A3I and A3II restore to normal. As the bails B0I, B0II and B3II are all returning to home position, the contacts 0a remain opened. The bails B0I and B3I return more quickly to home position than the bails B0II and B3II, so that the contacts 1b are already closed by the bails B0I and B3I while the contact 1a is still kept closed by the bail B0II so that the winding 1I receives current by which the armature A1I is attracted and the bail B1I is moved out of home position. The contacts 1a are kept closed by the bail B1I. The return of the bail B0I causes the opening of the contacts 0c, the return of the bail B1I closing the contacts 1c, the return of the bails B0I and B3I the closing of the contacts 2b, the return of the bail B3I the opening of the contacts 3c, the return of the bails B0II and B3II an opening of the contacts 4, and the return of the bails B0II and B3I a closing of the contacts 5. Thereupon the impulse emitter JII causes a current flow through contacts 1c and the winding 1II. The armature A1I remains attracted in spite of the deenergization of the winding 1I, and the armature A1II is attracted. The bail B1II being moved out of home position opens the contacts 0b and closes the contacts 2a. Of all the total contacts, now only contacts 5 are closed.

After the digit point of time "4" the impulse emitter JI supplies current through the contacts

1a and 1b to the winding 1I and through the contacts 2a and 2b to the winding 2I. While the winding 1II is currentless, the magnet M1 is energized by the winding 1I, so that the armatures A1I and A1II remain attracted. The current flow through the winding 2I causes an attraction of the armature A2I, the bail of which B2I closes the contacts 2c. By the substitution of the current supply through the impulse emitter JII, the winding 1II receives current through the contacts 1c, and the winding 2II through the contacts 2c. Thereby the magnet systems M1 and M2 remain energized despite the deenergization of the windings 1I and 2I, i. e., in such a way, that in addition to the armatures A1I, A1II and A2I the armature A2II is also attracted. The bail B2II, which is then moved out of home position, opens the contacts 5 and closes the contacts 3a and permits, in view of the bail B1II also being out of home position, the closing of the total contacts 6.

After the digit point of time "3," the winding 1I obtains current from the impulse emitter JI through the contacts 1a and 1b, and the winding 3I through the contacts 3a. The winding 1II becomes currentless but the magnet system M1 remains energized on account of the current flow through the winding 1I, so that the armatures A1I and A1II remain attracted. The current flow through the winding 3I causes an attraction of the armature A3I. Thus as the bail B3I is moved out of home position, it effects in common with the bail B1I acting on the spring plate 25, opening of the contacts 2b. Thus the current supply to the winding 2I is interrupted so that, as the winding 2II is also currentless, the magnet M2 is deenergized and its armatures A2I and A2II are returned to their home position. The bail B3I closes the contacts 3c. The total contacts 6 are opened by the bail B2II and the contacts 2c by the bail B2I. Thereupon the impulse emitter JII transmits current through the contacts 1c to the winding 1II and through the contacts 3c to the winding 3II. The magnets M1 and M3 then become fully energized so that the armatures A1I, A1II and A3I remain attracted and armature A3II is attracted. The bail B3II which is moved out of home position, closes the contacts 0a, opens the contacts 3a, and permits in common with the bail B1II the opening of the contacts 1a and the closing of the total contacts 7.

As at the digit point of time "2," the contacts 1a and 3a are opened, the winding 1I and also the winding 3I are no longer energized by the impulse emitter JI, and the windings 1II and 3II become currentless. Thereby the magnets M1 and M3 are deenergized, so that their armatures A1I and A1II, A3I and A3II restore to normal. The restoration of the armature A3II causes opening of the contacts 0a. Simultaneously the falling away of the armature A1II causes a closing of the contacts 0b. As the contacts 0b are thus opened before the contact 0a is closed, a current flow through the winding 0I does not take place. By virtue of the falling away of the armature A3I, its bail B3I causes the contacts 2b to close before the contacts 2a are opened. In the meantime the impulse emitter JI energizes the winding 2I, so that the armature A2I is attracted. The bail B2I, instead of the bail B1II, effects the closing of the contacts 2a and also closes the contacts 2c. The return of the bail B1I causes an opening of the contacts 1c, the return of the bail B3I an opening of the contacts 3c, and the return of the

bails **B₁II** and **B₃II** an opening of the contact **1** and a closing of the contacts **8**. The impulse emitter **JII** energizes the winding **2II** through contacts **2c**, now closed. As the winding **2I** becomes currentless, the winding **2II** energizes the magnet **M₂** alone, i. e., in such a way that besides the armature **A₂I** also the armature **A₂II** is attracted. Its bail **B₂II** closes the contacts **3a** and opens the contacts **0b**. Total contacts **8** remain the only total contacts which are closed.

After the digit point of time "1" the winding **2I** is energized by the impulse emitter **JI** through the contacts **2a** and **2b** and the winding **3I** through the contacts **3a**. The winding **2II** becomes currentless while the winding **2I** energizes the magnet system sufficiently to keep the armatures **A₂I** and **A₂II** attracted. The current flow through the winding **3I** causes an attraction of the armature **A₃I**. Its bail **B₃I** then closes the contacts **3c** and **9**. At this time the impulse emitter **JII** transmits current through contacts **2c** to the winding **2II** and through the contacts **3c** to the winding **3II**. Thereby the armatures **A₂I** and **A₂II** and **A₃I** are kept attracted in spite of the deenergization of the windings **2I** and **3I**, and the armature **A₃II** is also attracted. The bail **B₃II** being thus moved out of home position causes a closing of the contact **0a** and causes in common with the bail **B₂II** a closing of the contact **z** and an opening of the contact **2a**. The bail **B₃II** opens also the contacts **3a** and **8**. Of all the total contacts, there are finally only contacts **9** and **z** closed.

Besides the described operations with the changing influence on the relay by the impulse emitters **JI** and **JII** through the effect of the impulse emitter **JI** on various occasions, individual total contacts (**0**, **1**, **5** and **8**) were closed and under the influence of the impulse emitter **JII** thereafter opened again. These contact closings are, however, immaterial as before the digit points of time following them they are broken again and as these total contacts do not control any changes in the condition of the magnets. Thus, the closings of contacts **0** after the digit points of time "5" and "2," of contacts **1** after the digit points of time "6" and "5," contacts **5** after the digit points of time "9" and "2" and contacts **8** after the digit points of time "9" and "5" have no material effect.

At the end of the last current impulse of the impulse emitter **JII**, the digit point of time "0" is also over, so that the brush relay falls away. The contacts **BR_{2b}**, **BR_{2c}**, and **BR_{2d}**, are then returned again to the position in Fig. 4a, so that a permanent current from the positive line **45** over the conductor **57**, the contact springs **55**, **54** energizes the magnet system and keeps the windings **2II** and **3II**, energized during the previous impulse transmission, under current. Therefore the contacts **0a**, **1b**, **2b**, **2c**, **3c**, **9** and **z** remain likewise closed. This contact combination corresponds to the digit value "9," in accordance with the entry of a "9" into the magnet system of the calculating position being handled. The closed total contacts **9** would cause a print of the digit "9" upon the closing of the printing bank contacts **SWK**.

If shortly before time **E** (Fig. 6), i. e., at the index point of time "2," (Fig. 5) the entry of a "2" is started into the calculating position, in a manner similar to the entry of a "9" which just was described, from the time **E** or when the brush relay was energized with the entry and therewith contacts, such as **BR_{2b}**, **BR_{2c}** and **BR_{2d}** were

operated, the magnet system is brought again under the effect of the impulse emitters **JI** and **JII** up until the time **F**. First the impulse emitter **JI** energizes the magnet system from the digit point of time "2." As the holding circuits for the windings **2II** and **3II** are opened by the brush relay, these windings become currentless. As no further windings are energized, the armatures of the magnets **M₂** and **M₃** drop so that all bails of the system are moved to home position. Thereby contacts **0a**, **2c**, **3c** are opened and the contacts **0b**, **N**, **0**, **1**, **5**, and **8** are closed. At this time a current supply for the winding **3II** from the impulse emitter **JII** through contacts **N** is effected. In this manner the magnet **M₃** is energized so that its armatures **A₃I** and **A₃II** are attracted. The bail **B₃I** is moved out of home positions, closes the contacts **2c**, and opens the contacts **N** and **5**. The bail **B₃II**, which is likewise moved out of home position, closes the contact **0a** and opens the contacts **1** and **8**. Contacts **0** remain as the only total contacts closed, i. e., the relay corresponds in the present position of its contacts to the digit value "0." This position was already reached at the point of time **C** of Fig. 6, before the calculating device had been energized at all. From the digit point of time "1" up to the digit point of time "0" with the example of the entry of a "2" into the calculating position the same operation is effected, as with the example of the entry of a "9" into the calculating position between the digit points of time "9" and "8." Thus at the point of time **F** (Fig. 6) there exists a contact combination, corresponding to the digit value "1," i. e., to the unit value of the product of the addition **9+2**.

If a tens transfer from the position of the next higher order to the calculating position which is in issue is required, in the latter, as already described, after the digit point of time "0" (Fig. 5) up to the digit point of time "11" the brush relay is energized, whereby the magnet comes under the control of the impulse emitters. In Fig. 6 between **F** and **G** the effect of the tens transfer upon the relay in question is shown.

The contact positions are assumed for the purpose of the described examples and existing during the point of time **F** correspond to the digit value "1." This digit value was already represented between **C** and **D** at the digit point of time "8" by these contact positions. Exactly as these positions were changed up to the digit point of time "7" to the contact positions corresponding to the digit value "2" under the influence of the impulse emitters, also during the interval between **F** and **G** are the contact positions changed to the value "2" since during the latter time the brush relay contacts **BR_{2b}**, **BR_{2c}**, and **BR_{2d}** are switched over. If these contacts are returned to their home positions following the deenergization of the brush relays, the above contact positions are maintained by the permanent current over wires **57**, **55**, and **54**. The value "2" accumulated in the relay of the calculating position may then be printed in the printing bank.

A tens carry is effected in all calculating positions simultaneously in which the brush relay is energized after the digit point of time "0" (Fig. 5) until after the digit point of time "11." This may occur under certain conditions also in successive positions, in accordance with the description of the connections for the tens transfer relays **UR₁**, **UR₂**, etc., given hereinbefore.

In the second form of embodiment of the invention shown in Figs. 7, 8, and 9, the connec-

tions for the relays are effected in such a way that tens transfer operations take place at once, when they are required, i. e., between the individual digit points of time. In Fig. 7 a calculating example is demonstrated, at which points of time differential tens carry operations occurring in the example are effected. For the purpose of the example it is assumed that the position of the contacts of the individual magnets in the calculating device is such that the figure 02206979588 is standing therein. To this figure, during the value entry operation, the figure 07808369192 has to be added, so that the calculating device indicates thereafter the figure 10015348780 by the position of its contacts. The individual positions of the calculating device are represented in the Fig. 7 by vertical columns and are designated on the first line. The digits on the second line of Fig. 7 indicate the digit value entered in the calculating device before the adding operation. In each vertical column there are indicated, independent of the digit points of time "9"- "0" entered at the left of Fig. 7, the digit values entered in the corresponding calculating positions during the adding cycle. The black circular areas in the individual columns indicate points of time, during which, the record card analyzation and entry of digit values into the different calculating positions are effected. The diagonally crosshatched portions of the columns show when the respective calculating position is in motion on account of the adding of a value. The horizontally crosshatched portions of the columns indicate that at the designated times tens carry operations from one position to the position of the next higher order or successively to several positions of the next higher order are effected.

For the entry of values in the manner shown in Fig. 7 in addition to impulse emitters JI and JII there are provided still two further impulse emitters JIII and JIV. The impulse emitters JIII and JIV serve for the tens carry and are operative prior to the impulse emitters JI and JII between two digit time intervals, as indicated at the left of Fig. 7.

With the start of the value entry, according to the example shown in Fig. 7, in the fourth calculating position, the contact combination is set to the value "9" from which it has to be changed at once at the beginning of the adding cycle on account of the entry of a "9" in this position of the value "0." Thereby a tens carry A to the position 5 is necessary and takes place prior to the change of the combination in the fourth position from "9" to "0." In the same manner the tens transfer B from the second position to the third position is effected. With the tens carry C, starting from the fifth position, a carry to the positions 6, 7, and 8 is necessary, since positions 6 and 7 are set to the value "9." The tens carry to the three calculating positions 6, 7, and 8 is effected simultaneously. The tens carry D is principally similar to the tens carry A and B with the difference that the position to which the numeral has to be added is in motion.

While the tens carry operations cited up to now are always occurring if in the positions for which a tens carry is necessary a "9" is entered, a tens carry is also demonstrated to occur if a calculating position, in the present case the position 10, is still set to the value "8" but in the course of the value entry operation would still change over to the value "9" and then go beyond the value "9." In the example E, the position 9

requires a tens carry to the position 10. As this position is set to "8" and is still in motion, a current tens carry is effected also to the position 11.

6 The application of the tens carry points of time to the value entry cycle requires changes in the connections of Figs. 4 and 4a. The wiring diagram on which these changes are effected is shown on Fig. 8. Fig. 8 shows only those portions of Figs. 4, 4a which are necessary to illustrate the changes in the wiring diagram.

15 According to Fig. 8 the brush relay of each position is under the influence of a value entry device (see plug socket 42) and of the cam contacts N1 and N4 in the manner described for the first embodiment in regard to the calculating position of the lowest order. Also the common connection 49 of all windings of the magnets M0, M1, M2, and M3 and of the carry control relays UR1, UR2, etc., as well as the connection 20 through the resetting contact LK, the conductor 50 to the conductor 32 remain the same. The impulse emitters JI and JII are connected with the positive line 45 as before, and the impulse emitter JI is connected through wires 53 with the brush relay contacts BR1c, BR2c, etc., and the impulse emitter JII through the wires 58 with the brush relay contacts BR1d, BR2d. The lower contact springs 55 of the contacts BR1d, 25 BR2d, etc., are connected by the wires 51 with one another and with the conductor 45. Contacts BR1c of the calculating position of the lowest order are connected with the common bar 51, and the middle contact spring 54 of contacts BR1d is connected directly with the bar 52 of the contact system of the first calculating position.

30 In the second calculating position, the connection of the brush relay contact BR2c with the bar 51 through carry relay contacts UR1a, and 35 the connection of brush relay contacts BR2d with the bar 52 through carry relay contacts UR1b are effected. This arrangement of carry relay contacts indicated for the second position is provided for all further positions. The contacts 40 UR1a consist of an upper contact spring 80 (connected with BR2c), a middle contact spring 81 (connected with 51) and a lower contact spring 82. The corresponding contacts UR2a, etc., of the following positions are arranged in the same 45 manner. The contact springs 82 are connected with one another by wires 83 and also with an impulse emitter JIII. The contacts UR1b, UR2b, etc., consist each of an upper contact spring 84 (connected with BR2d, etc.), a middle contact 50 spring 85 (connected with 52) and a lower contact spring 86. The contact springs 86 are connected with each other by wires 87 and also with an impulse emitter JIV. The impulse emitters JIII and JIV are connected with positive line 45 55 as are emitters JI and JII. In addition to the conductor 83, a conductor 88 is connected with the impulse emitter JIII for effecting a supply of current to the tens carry relays UR1, UR2, etc., under the control of the impulse emitter JIII.

60 65 The energization of the carry control relays UR1, UR2 etc. is dependent upon the position of further brush relay contacts BR1e, BR2e, etc., and upon the position of the contacts z of the contact systems. The contacts z of the various contact systems are indicated in Fig. 8 in circuit 70 relation with the rest of the contact system and include contacts z1, z2, etc. The energization of carry relays UR2, UR3, etc., is furthermore dependent upon the brush relay contacts BR2f, 75 BR3f, etc., and upon special total contacts 8 which

are indicated in Fig. 8 according to which calculating positions they are associated with by the reference numerals 8 (2), 8 (3), etc.

If say in the lowest position the brush relay is energized as a result of a value entry therein and therewith its contact BR_{1e} is closed, and the contact combination for this position is set to the value "9" (in which case contacts z₁ are closed), then the transfer relay UR₁ is energized by an impulse transmitted from impulse emitter JIII. If upon energization of UR₁, contacts z₂ are closed (contact combination at the value "9") and the brush relay contacts BR_{2e} are in the indicated position (no value entry in the second position), then the transfer relay UR₂ of the second position is energized simultaneously with UR₁. The same occurs, if in the second position contacts 8 (2) instead of contacts z₂ are closed (contact combination on the value "8") and brush relay contacts BR_{2f} are closed (upon value entry). If also in the third position, either z₃ is closed and BR_{3e} in the position shown or if 8 (3) is closed and BR_{3e} and BR_{3f} shifted, then along with the carry relays UR₁ and UR₂, the carry relay UR₃ of the third position is also energized.

The preliminary conditions for the energization of the carry relay of the lowest position (see tens carry D in Fig. 7) apply also to the other positions (see tens carries A, B, C and E in Fig. 7). The described conditions for the energization of the carry relays of the positions following the lowest position apply also to the position following a position being ready for the passing from "9" to "0" (compare tens carry C and E in Fig. 7). The energization of carry relays of individual positions on the basis of the described conditions establishes, by virtue of the shifting of its contacts (f. i., UR_{1a} and UR_{1b} or UR_{2a} and UR_{2b}), a connection between the impulse emitters JIII, JIV and the magnets of the relay of the next higher position coordination.

If a value entry into a calculating position at a predetermined digit point of time is effected, thereupon, the same as with the first form of embodiment, between two digit points of time a switching of the relay of this position by one digit value takes place, i. e., a change from one contact combination corresponding to a digit value to a contact combination corresponding to the next higher digit value. This is done upon the energization of a brush relay, for example that of the lowest position by a current impulse from the impulse emitter JI through brush relay contacts BR_{1c} to the bar 51 of the relay and by a current impulse from the emitter JII connected thereto through brush relay contacts BR_{1d} to the bar 52 of the relay. Upon energization of the brush relays of the following positions the impulse emitters JI and JII are rendered effective through the brush relay contacts BR_{2c} and BR_{2d}, BR_{3c}, and BR_{3d}, etc.

For the tens carry operations the switching of the respective relays by one digit value is effected by the impulse emitters JIII and JIV, whereby JIII transmits first a current impulse to the bar 51 and then JIV a current impulse to the bar 52 of the corresponding relay. The operations of each relay by the current impulses successively supplied to the bars 51 and 52 have already been explained with reference to Fig. 6. It is thereby immaterial whether these current supplies are controlled by the impulse emitters JI and JII or by the impulse emitters JIII and JIV.

During each value entry cycle between two digit points of time the impulse emitters become 75

effective in the following order: JIII, JIV, JI, JII. This means that when tens carries are necessary between two digit points of time, first the tens carry and then the switching on account of the value entry is effected, so that in each position which is in motion and which is to receive a tens carry the corresponding relay is operated in the interval between two digit points of time to an extent indicative of an entry of two unit values. If in a particular position a tens carry is necessary even though no value entry has been effected in this position, the relay is operated only to the extent of one digit value, under the influence of the impulse emitters JIII and JIV between two index points of the time. The closing times of the impulse emitters JI, JII, JIII and JIV are represented in Fig. 9 by crosshatched areas. The effect of the impulse emitters JIII and JIV upon the relays of the second, third, etc. position is dependent on the position of the contacts UR_{1a}, UR_{1b}, UR_{2a}, UR_{2b}, etc., of the carry control relays of the next lower position (UR₁, UR₂, etc.).

If, for example, the carry relay UR₁ of the first position is energized so that its contacts UR_{1a} and UR_{1b} are switched over from the position shown in Fig. 8, the relay of the second position is connected through the contact springs 81 and 82 with the impulse emitter JIII and through the contact springs 85 and 86 with the impulse emitter JIV, so that the impulse emitters JIII and JIV may switch the relay to the extent of one digit value.

During the return of the contacts UR_{1a} and UR_{1b} to their home position, caused by the de-energization of the transfer relay UR₁ at the end of the current impulse from the impulse emitter JIII and following the shifting of the contact springs 84, 85, and 86, all the contact springs are connected with one another so that upon the contact closing effected by the current supply from the impulse emitter JIV, no interruption to the relay occurs and upon a premature termination of the switch over, a replacement of the impulse emitter JIV by the impulse emitter JII takes place to provide for the proper termination of the current impulse.

If a relay is switched by the impulse emitters JIII and JIV by one digit value to effect a tens carry and if a further switching on account of value entry is required, this is effected in connection with the tens carry in the already described manner under control of the impulse emitters JI and JII.

While there has been shown and described and pointed out the fundamental novel features of the invention as applied to two embodiments, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. An electrical relay accumulator for a calculating machine in which digital entries are effected in different denominational orders thereof comprising, in each denominational order, a plurality of electromagnets, each having a pair of windings of different strengths, there being an armature for each winding, operable upon energization of the related winding, the winding of greater strength for each magnet operating both related armatures of the corresponding magnet,

a plurality of pairs of contacts adjustable to open or closed position, certain of which are adjusted independently by one armature, others by one or more armatures, and others by the joint action of more than one armature, each of the digits being represented by a different relative adjustment of said plurality of pairs of contacts, circuit connections between the pairs of contacts and the magnet windings, arranged so that for each digit representing adjustment of the pairs of contacts different circuit paths are established through the contacts to the windings to effect a change in the adjustment of the contacts to represent the next higher digit, impulse emitting means for transmitting a plurality of successive impulses through the contacts and windings whereby each digit will be represented in turn, means for selectively controlling the number of impulses transmitted whereby an initial digital setting of the contacts will be advanced a number of digits in accordance with the number of impulses transmitted; and means controlled by the contacts of lower orders when a lower order setting passes from 9 to 0 for causing said emitting means to cause entry of an additional unit in the higher order magnets.

2. An electrical relay accumulator for a calculating machine in which digital entries are effected in different denominational orders thereof comprising, in each denominational order, four electromagnets, each having a pair of windings of different strengths, there being an armature for each winding, operable upon energization of the related winding, the winding of greater strength for each magnet operating both related armatures of the corresponding magnet, a plurality of pairs of contacts adjustable to open or closed position, certain of which are adjusted independently by one armature, others by one or more armatures, and others by the joint action of a pair of unrelated armatures, each of the digits being represented by a different relative adjustment of said plurality of pairs of contacts, circuit connections between the pairs of contacts and the magnet windings, arranged so that for each digit representing adjustment of the pairs of contacts different circuit paths are established through the contacts to the windings to effect a change in the adjustment of the contacts to represent the next higher digit, impulse emitting means for transmitting a plurality of successive pairs of impulses through the contacts and windings, the impulses of each pair being also in successive order, whereby each digit will be represented in turn, means for selectively controlling the number of pairs of impulses transmitted whereby an initial digital setting of the contacts will be advanced a number of digits in accordance with the number of pairs of impulses transmitted; and means controlled by the contacts of lower orders when a lower order setting passes from 9 to 0 for causing said emitting means to emit an additional pair of carry impulse to the higher order magnets.

3. An order of an electrical accumulator comprising a plurality of electromagnets, each having a pair of windings of different strengths, a plurality of pairs of contacts adjustable under control of said windings to open or closed position, certain of which pairs of contacts are adjusted upon energization of one winding, others upon energization of one or more windings and others upon the joint energization of more than one winding, energization of any winding of greater strength causing the contacts of the related winding of lesser strength to become adjusted, each

5 of the digits being represented by a different relative adjustment of said plurality of pairs of contacts, circuit connections between the pairs of contacts and the magnet windings, arranged so that for each digit representing adjustment of the pairs of contacts different circuit paths are established through the contacts to the windings to effect a change in the adjustment of the contacts to represent the next higher digit, impulse emitting means for transmitting a plurality of successive impulses through the contacts and windings whereby each digit will be represented in turn, means for selectively controlling the number of impulses transmitted whereby an initial digital setting of the contacts will be advanced a number of digits in accordance with the number of impulses transmitted.

10 4. An order of an electrical accumulator comprising a plurality of electromagnets each having a pair of windings, a plurality of pairs of contacts adjustable under control of said windings to open or closed position, certain of which pairs of contacts are adjusted upon energization of one winding, others upon energization of one or more windings and others upon the joint energization of more than one winding, energization of any one of a pair of windings causing the contacts of the other of the windings to become adjusted, each of the digits being represented by a different relative adjustment of said plurality of pairs of contacts, circuit connections between the pairs of contacts and the magnet windings, arranged so that for each digit representing adjustment of the pairs of contacts different circuit paths are established through the contacts to the windings to effect a change in the adjustment of the contacts to represent the next higher digit, impulse emitting means for transmitting a plurality of successive impulses through the contacts and windings whereby each digit will be represented in turn, means for selectively controlling the number of impulses transmitted whereby an initial digital setting of the contacts will be advanced a number of digits in accordance with the number of impulses transmitted.

15 5. The invention set forth in claim 2 in which a set of ten result indicating contacts are provided, one for each digit in a decimal notation, each contact having an indicating and a non-indicating position, connections between said contacts and said armatures so arranged that certain contacts are adjusted to indicating position by a single armature and others by the joint action of more than one armature, concurrently with the adjustment of the first named plurality of pairs of contacts whereby the result indicating contacts will progressively indicate the digit values corresponding to the progressive adjustment of said first named plurality of pairs of contacts.

20 6. An order of an electrical relay accumulator, comprising four electromagnets each having a pair of windings, a set of twelve pairs of contacts, electrical connections between the contacts and windings, each winding upon energization causing a different relative adjustment of said pairs of contacts, the digits in a decimal notation being each represented by the energization of the four electromagnets in combinations of one or two, impulse emitting means for transmitting a predetermined number of pairs of electrical impulses through said connections and windings, each pair of impulses effecting a combinational energization of the electromagnets representative of the next higher digit whereby the initial digital set-

ting will be advanced in accordance with the number of impulses transmitted.

7. An order of an electrical relay accumulator comprising a plurality of electromagnets on which all digital values are represented electrically by the energization of said magnets in combinations of one or two magnets, a plurality of pairs of contacts operated by said magnets to take a different relative adjustment for each digit representation, circuit connections between the contacts and magnets, means for transmitting impulses through said connections, the adjustment of the contacts serving to direct the impulses to energize the magnet or magnets to represent a higher digit.

8. An accumulating system in which digit values are represented electrically by the energization of relays in combination code comprising of each denominational order, a plurality of relays less in number than the number of digits in a decimal notation, a plurality of contacts, each relay effecting adjustment of a number of said contacts, the adjustment of certain of which is also effected by others of the relays, controlling connections actuated by the relays for adjusting the contacts, circuit connections interconnecting the contacts and relays arranged to control energization of the relays singly or in pairs, to represent the different digits, means for transmitting impulses through said circuit connections to initiate an entry in said relays, said impulses causing erasure of a previous digital setting of the relays and effecting a new setting representing a higher digit.

9. The invention set forth in claim 8 in which record controlled means is provided to cause repeated operation of said impulse transmitting means to send repeated impulses through said circuit connections whereby the relays will be selectively energized through the contacts and will in turn adjust the contacts to represent the digits in succession.

10. The invention set forth in claim 8 in which there is a pair of carry contacts for each order of the accumulator actuated by said relays when an entry of 9 is represented and means controlled by the transmitting means of each order and said carry contacts for causing the

transmitting means of the next higher order to advance the setting thereof one digit.

11. An accumulating system in which digit values are represented electrically by the energization of relays in combination code comprising for each denominational order, a plurality of relays, a plurality of contacts, each relay effecting adjustment of a number of said contacts, the adjustment of certain of which is also effected by others of the relays, controlling connections actuated by the relays for adjusting the contacts, circuit connections interconnecting the contacts and relays arranged to control energization of the relays singly or in pairs, to represent the different digits, means for transmitting impulses through said circuit connections to initiate an entry in said relays, said impulses causing erasure of a previous digital setting of the relays and effecting a new setting representing a higher digit.

12. An accumulating system in which digit values are represented electrically by the energization of relays in combination code comprising for each denominational order, a plurality of relays, a plurality of contacts, each relay effecting adjustment of a number of said contacts, the adjustment of certain of which is also effected by others of the relays, controlling connections actuated by the relays for adjusting the contacts, circuit connections interconnecting the contacts and relays, arranged to control energization of the relays in the digit representing combinations different for each of the digits, an entry impulse transmitting means for transmitting a succession of impulses concurrently through said circuit connections in each order, impulses in an order causing erasure of the relay setting and energization of the relays in accordance with the next higher digit, a tens carry impulse transmitting means, and means rendered effective when the relay setting of an order passes from 9 to 0 for rendering the tens carry impulse transmitting means effective to transmit impulses through the circuit connections of the next order prior to the next succeeding entry impulse in that order.
